CLAIM

We claim the ornamental design for the pet toy, as shown and described.

DESCRIPTION

FIG. 1 is a perspective view of a pet toy in accordance with the present design;

FIG. 2 is a front elevational view thereof;

FIG. 3 is a back elevational view thereof;

FIG. 4 is a left side elevational view thereof;

FIG. 5 is a right side elevational view thereof;

FIG. 6 is a top plan view thereof; and,

FIG. 7 is a bottom plan view thereof.

Features shown in broken lines depict environmental subject matter, are for illustration only and form no part of the claimed design. The long dash short dash broken line represents a claim boundary line and forms no part of the claimed design.

1 Claim, 7 Drawing Sheets
